UNITED STATES PATENT OFFICE.

WILLIAM RUFF, OF NEW YORK, N. Y.

HOSPITAL BED.

Application filed June 20, 1922. Serial No. 569,653.

To all whom it may concern:

Be it known that I, WILLIAM RUFF, a citizen of the United States, residing at the borough of Manhattan, in the city, county, 5 and State of New York, have invented certain new and useful Improvements in Hospital Beds, of which the following is a specification, reference being had therein to the accompanying drawings, which form a 10 part thereof.

My invention relates to hospital beds, and more particularly to a bed structure wherein in the mattress or its support may be mechanically turned to facilitate cleaning of 15 the bed and may be so set as to promote the comfort of the occupant, a supplemental seat being provided to facilitate the handling of a patient by a nurse or nurses.

Heretofore it has been suggested that 20 beds be so constructed as to permit the mechanical elevation and turning of a mattress or its support to facilitate its inspection and cleaning, and it has been common to provide davenports or extension beds so 25 as to permit a nurse to rest while in attendance upon a patient. The bed of my invention, however, is so constructed that the means for raising the mattress or its support may also be utilized to elevate it towards 30 either the head or the foot of the bed to promote the comfort of the occupant, or to ensure a posture which may be necessary if not comfortable, the supplemental seat being provided merely for temporary use and 35 being adjustable vertically so as to accommodate it to the occupant of the bed, the seat while not in use being adapted to be moved under the bed.

The invention consists primarily in a hospital bed embodying therein a head piece, a 40 foot piece, side rails, one of which is rotatable, a mattress carrier, an arm pivoted thereto and connected with said rotatable side rail, means whereby the side rail to 45 which said arm is connected may be rotated, and a seat supported from and adjacent a side rail; and in such other novel features of construction and combination of parts as are hereinafter set forth and described, and 50 more particularly pointed out in the claims hereto appended.

Referring to the drawings,

Fig. 1 is an end view of a bed embodying 55 my invention with portions thereof broken away; and

Fig. 2 is a side view thereof with the seat positioned beneath the bed.

Like letters refer to like parts in both of said views.

In the embodiment of the invention as 60 shown in the drawings, *a* indicates the head piece of a bed, *b* the foot piece thereof, and *c* and *d* the side rails, one of which as *c* is rotatably mounted in relation to the head and foot pieces. The mattress carrying 65 member, as a box spring, is shown at *e*.

Substantially midway between the sides of the member *e* and at opposite ends thereof, are pivots *e'* and *e''* to which are connected the arms *f*—*f'* carried by the side rail *c*, and secured thereto by means of strong pins *f*²—*f*³ so that either of said arms may be disconnected from said side rail to make the arm so disconnected, inoperative for the 70 purpose of elevating the member *e*.

Means are provided whereby the said side rail *c* may be rotated, said means in the form of the invention shown consisting of a worm gear *g* carried by said rail, and a worm shaft *g'* co-operating therewith and 75 carried by either the head or the foot piece of the bed.

Pivotedly mounted upon the other side rail *d*, are guide arms *h*—*h'* having slidably 80 mounted thereon a frame *i* carrying a seat *j* which may be of any desired construction, the frame *i* having grooved portions *i'* by means of which it is slidably mounted upon 85 said guide arms *h*—*h'*. Pivotedly mounted upon the side rail *c* are lever arms *k*—*k'*, 90 the ends of which respectively are pivoted to the lever arms *m*—*m'* carried by and rotatable with a shaft *n* mounted in the guide arms *h*—*h'* adjacent the free ends thereof, 95 which construction permits vertical adjustment of said arms *h*—*h'* and the seat *j* supported therefrom. To permit the proper movement of said arms *h*—*h'*, they are bent as shown more particularly in Fig. 1 of the 100 drawings, so that when the seat is not required for use, said guides will present a substantially horizontal portion of sufficient length to permit the seat to be slid thereon beneath the mattress carrying member *e*.

The vertical adjustment of said seat through the guide arms *h*—*h'* is effected by means of a worm gear *o* keyed or otherwise secured to the shaft *n*, and a worm shaft *o'* mounted in bearings in the end of the guide arm *h* 110 and co-operating with said gear *o*.

A crank handle p is provided which may be fitted to the squared end of either worm shaft g' or o' .

The operation of the herein described hospital bed is substantially as follows:—

Under ordinary conditions the worm gear g and worm shaft g' will position the member e as shown in Fig. 1, the opposite sides of said member e resting upon the side rails c and d so as to relieve the arms $f-f'$ from the load of said member and of an occupant of the bed. When the parts are so set, the seat j will be positioned beneath the member e , the frame i sliding freely upon the arms $h-h'$, which are of sufficient length to permit this positioning of the seat.

It will be readily understood that the spring e may be an ordinary wire or box spring or a mattress spring, as desired, and that its construction is immaterial to the invention.

If it be desired for the comfort of the patient, to elevate either the head or the foot of said member e , either pin f^3 or f^2 may be removed so as to disengage the arm f' or f from the rotatable side rail c before the worm gear g is operated by the worm shaft g' and the crank handle q , to rotate the member e and thus raise the arm f or f' still connected therewith sufficiently to give a longitudinal tilt to the entire structure e . While the end of the arms thus operative may describe a slight arc, the lateral component of movement of the member e will not be sufficient to materially disturb that end thereof which is not elevated, or disengage it from the side rails of the bed structure.

If it be desired to merely inspect the member e and clean same, both pins f^2 and f^3 are used to connect both arms f and f' to the rail c thus causing the actuation of said rail to raise the member e in its entirety, the length of the arms f and f' being such that when they are brought to a substantially vertical position as shown in Fig. 2, the member e will be positioned adjacent and above the side rail c so as to be readily turned for purposes of inspection or cleaning.

It is essential that the arms f and f' have considerable rigidity, since in a full sized bed they are required to be at least two feet long and are thus subjected to a considerable load.

The worm gear g and worm shaft g' are used so as to prevent any possible slippage in raising or lowering the member e in its entirety, or in raising one end thereof only, as well as to secure a self-locking mechanism which will ensure the maintenance of the arms f and f' in any position to which they may be brought.

When it is desired to use the seat j , said seat is drawn outwardly from beneath the

member e by moving the frame i along the guide arms $h-h'$. When so drawn from beneath the member e , however, the position of said seat will be so low as to have no utility, it being essential to elevate it to approximately the level of the member e , or the mattress thereon, if such be used. To secure the desired adjustment of said seat j , the worm shaft o' is actuated by means of the handle g to turn the worm gear o secured to the shaft n . This movement of the shaft n will be in a direction to move the ends of the arms $m-m'$ pivoted to the lever arms $h-h'$ respectively, downwardly, or a clockwise movement of the shaft n as shown in Fig. 1, and will result in an upward pivotal movement of the lever arms $h-h'$ and guide arms $h-h'$, the angular formation of the last named arms causing an outward movement of the seat j sufficient to compensate for the arc described by the shaft n , and the links k adjusting themselves to the arc of movement of the arms $m-m'$ and $h-h'$.

The worm gear and worm shaft construction $o-o'$ is used not so much as a speed reducing mechanism, as to ensure against possible slippage of the actuating means and provide a positive lock to prevent loads upon the seat j causing its displacement and possible injury to the patient or other occupant thereof.

With the initial elevation of the seat j , movement thereof inwardly of the bed will be prevented by the side rail c .

The seat j may be constructed in any desired manner and may be provided with a hinged cushion seat as shown in the drawings, if so desired.

When brought to the proper elevation, said seat will serve as a great convenience when handling a patient upon the bed, or to an attendant upon a patient.

To restore the seat to a position where it will not be in the way after it has been in use, the worm shaft o' and worm gear o may be used to turn the shaft n in the reverse direction to that used when elevating the seat j and its guide arms $h-h'$; causing an upward movement in arc of the arms $m-m'$ and a downward movement of the lever arms $h-h'$ and the guide arms $h-h'$ until said guide arms have been brought to the desired level to permit the seat j and its frame i to be moved inwardly thereupon beneath the side rail c and the member e .

It will be observed that the level of the seat j may be varied to suit the requirements of a patient, this variance in the position of said seat being in relation to the member e .

Notwithstanding the use of rotatable members and gears for affecting an adjustment of the member e and of the seat j ,

absolute rigidity in this structure is secured at all times and accidental or rapid movement of these parts is prevented.

If when handling a patient, it is desired 5 to tilt the member *e* laterally of the bed, the patient may be placed upon the member *e* adjacent the side rail *c* and said side rail turned while the arms *f*—*f'* are secured thereto by the pins *f*² and *f*³ respectively, 10 until the desired lateral inclination of the member *e* has been secured.

It will be observed that the seat *j* is materially shorter in length than the member *e*, and is not designed nor suitable for use 15 as a cot for the attendant, the dimensions of said seat approximating those of the seat of a small chair.

The actuating mechanisms employed will ensure a slow movement of all parts, so 20 that a patient cannot be disturbed by a too rapid movement, particularly of the member *e*.

It is not my intention to limit the invention to the precise details of construction shown in the accompanying drawings, 25 it being apparent that such may be varied without departing from the spirit and scope of the invention.

Having described the invention, what I 30 claim as new and desire to have protected by Letters Patent, is:—

1. A hospital bed embodying therein a head piece, a foot piece, side rails, one of 35 which is rotatable, a mattress carrier, an arm pivoted thereto at each end thereof and connected with said rotatable side rail, and means whereby the side rail to which said arms are connected may be rotated.

2. A hospital bed embodying therein a 40 head piece, a foot piece, side rails, one of which is rotatable, a mattress carrier, an arm pivoted thereto at each end thereof and connected with said rotatable side rail, means whereby either of said arms may be 45 disconnected from said side rail to permit the elevation of only one end of the carrier, and means whereby the side rail to which said arms are connected may be rotated.

3. A hospital bed embodying therein a 50 head piece, a foot piece, side rails, one of which is rotatable, a mattress carrier, an arm pivoted thereto at each end thereof and connected with said rotatable side rail, a worm gear carried by said rotatable side rail, and a worm shaft co-operating therewith whereby the side rail to which said arms are connected may be rotated.

4. A hospital bed embodying therein a 60 head piece, a foot piece, side rails, one of which is rotatable, a mattress carrier, an arm pivoted thereto at each end thereof and connected with said rotatable side rail, means whereby either of said arms may be disconnected from said side rail to permit

the elevation of only one end of the carrier, 65 a worm gear carried by said rotatable side rail, a worm shaft co-operating therewith whereby the side rail to which said arms are connected may be rotated, and a seat supported from and adjacent a side rail. 70

5. A hospital bed embodying therein a head piece, a foot piece, side rails, one of which is rotatable, a mattress carrier, an arm pivoted thereto at each end thereof and connected with said rotatable side rail, 75 means whereby the side rail to which said arms are connected may be rotated, guide arms pivotally mounted upon the other side rail and extending adjacent said rotatable side rail, a seat carrying frame slidably 80 mounted upon said guide arms, and means whereby said guide arms may be raised or lowered to adjust the elevation of the seat upon said frame with relation to said mattress carrier.

6. A hospital bed embodying therein a head piece, a foot piece, side rails, one of which is rotatable, a mattress carrier, an arm pivoted thereto at each end thereof and connected with said rotatable side rail, means 90 whereby the side rail to which said arms are connected may be rotated, guide arms pivotally mounted upon the other side rail and extending adjacent said rotatable side rail, a seat carrying frame slidably mounted upon said guide arms, lever arms pivotally mounted upon said rotatable side rail, a shaft carried by said guide arms, lever arms carried thereby and pivotally connected with said first named lever arms respectively, and means whereby said shaft may be rotated to raise or lower said guide arms and adjust the seat upon said seat carrying frame with relation to the mattress carrier. 95

7. A hospital bed embodying therein a head piece, a foot piece, side rails, one of which is rotatable, a mattress carrier, an arm pivoted thereto at each end thereof and connected with said rotatable side rail, means whereby the side rail to which said arms are connected may be rotated, guide arms pivotally mounted upon the other side rail and extending adjacent said rotatable side rail, a seat carrying frame slidably 100 mounted upon said guide arms, lever arms pivotally mounted upon said rotatable side rail, a shaft carried by said guide arms, lever arms carried thereby and pivotally connected with said first named lever arms respectively, a worm gear carried by said shaft and a worm shaft co-operating therewith whereby said shaft may be rotated to raise 110

or lower said guide arms and adjust the seat upon said seat carrying frame with relation to the mattress carrier. 115

8. A hospital bed embodying therein a head piece, a foot piece, side rails, one of which is rotatable, a mattress carrier, an arm

15 pivoted thereto at each end thereof and connected with said rotatable side rail, means whereby the side rail to which said arms are connected may be rotated, guide arms pivotally mounted upon the other side rail and being so bent as to provide a substantially horizontal portion extending adjacent said rotatable side rail, a seat carrying frame slidably mounted upon the horizontal portion of said guide arms, and means whereby said guide arms may be raised or lowered to adjust the elevation of the seat upon said frame with relation to said mattress carrier.

15 9. A hospital bed embodying therein a head piece, a foot piece, side rails, one of which is rotatable, a mattress carrier, an arm pivoted thereto at each end thereof and connected with said rotatable side rail, a 20 worm gear carried by said rotatable side rail, a worm shaft co-operating therewith whereby the side rail to which said arms are connected may be rotated, guide arms pivotally mounted upon the other side rail and extending adjacent said rotatable side rail, a seat carrying frame slidably mounted upon said guide arms, lever arms pivotally mounted upon said rotatable side rail, a shaft carried by said guide arms, lever arms carried thereby and pivotally connected with said first named lever arms respectively, a worm gear carried by said shaft and a worm shaft co-operating therewith whereby said shaft may be rotated to raise or lower said guide arms and adjust the seat upon said seat

25 30 35

carrying frame with relation to the mattress carrier.

10. A hospital bed embodying therein a head piece, a foot piece, side rails, one of which is rotatable, a mattress carrier, an arm pivoted thereto at each end thereof and connected with said rotatable side rail, a worm gear carried by said rotatable side rail, a worm shaft co-operating therewith whereby the side rail to which said arms are connected may be rotated, guide arms pivotally mounted upon the other side rail and being so bent as to provide a substantially horizontal portion extending adjacent said rotatable side rail, a seat carrying frame slidably mounted upon the horizontal portion of said guide arms, lever arms pivotally mounted upon said rotatable side rail, a shaft carried by said guide arms, lever arms carried thereby and pivotally connected with said first named lever arms respectively, a worm gear carried by said shaft and a worm shaft co-operating therewith whereby said shaft may be rotated to raise or lower said guide arms and adjust the seat upon said seat

50 55 60

In witness whereof I have hereunto affixed my signature, in the presence of two subscribing witnesses, this 16th day of June, 1922.
